UNITED STATES PATENT OFFICE

170,331

FOLDING DESK CHAIR

Roy C. Moore, Dallas, Tex.

Application June 30, 1952, Serial No. 20,410

Term of patent 14 years

(Cl. D33—11)

To all whom it may concern:

Be it known that I, Roy C. Moore, a citizen of the United States of America, residing at Dallas, in the county of Dallas and State of Texas, have invented a new, original, and ornamental Design for Folding Desk Chair, of which the following is a specification, reference being had to the accompanying drawing, forming part thereof.

In the drawing

Fig. I is a perspective view of a folding desk chair, showing my new design;

Fig. II is a perspective view of the folding desk chair showing the subject in a folded position.

Fig. III is a perspective view of the folding desk chair taken from the opposite side of Fig. I.

I claim:

The ornamental design for a folding desk chair, substantially as shown.

ROY C. MOORE.
